HIGH-SPEED JACK.

1,329,665.

Specification of Letters Patent.

Patented Feb. 3, 1920.

Application filed July 15, 1919. Serial No. 310,965.

To all whom it may concern:

Be it known that we, JOHN C. KOPF and FRANK H. SCHWERIN, citizens of the United States, and residents, respectively, of the borough of Bellevue, in the county of Allegheny and State of Pennsylvania, and of the borough of West View, in the county of Allegheny and State of Pennsylvania, have invented a new and useful High-Speed Jack, of which the following is a specification.

The object of the invention is to provide an improved high-speed heavy-duty screw-jack. A high-speed screw-jack possesses a screw having a pitch beyond the angle of repose, so that the jack is self-lowering under load and will run down as fast as permitted by a self-locking lowering mechanism having an overrunning connection. A separate operating mechanism actuates the screw in the direction for lifting independently of the self-locking lowering means, which through the overrunning connection is ever ready to hold the screw against descent. Large jacks of this character with which we are familiar have been organized to carry their operating mechanisms in large overhanging rotatable heads, and have been dangerously top-heavy, awkward to move about and position, inconvenient to operate, and liable to bend their screws. The purpose of the present invention is to construct a jack of the kind specified which shall be non-toppling, strong and durable and protected in respect to its screw, easy to handle and convenient to operate, and which shall be well adapted for manufacture. In its preferred embodiment the jack has a relatively broad base with a relatively narrow hollow standard portion and a lower annex portion applied at the rear or side, all incased to be packed with grease, a ram slideable and held against rotation in the standard and bearing a relatively narrow head, a nut in the lower part of the ram, a steep-pitch screw rotatably supported on the bottom of the base and extending upward through the nut and freely within the ram, lifting means and self-locking lowering means with overrunning connection, all assembled in the annex of the base, and operating through a common vertical axis upon the lower portion of the screw. Means are

further provided for coupling the lowering means with the vehicle shaft in order to effect positive lowering of the ram when the latter is free of load and will not descend of itself. 55

A further object is to minimize sink-back of the load-lifting member or ram after each stroke of the lifting handle. This is accomplished by means of what may be termed a vernier or graduated action overrunning clutch between the self-locking means and the screw, having a plurality of pawls which 60 act successively so that the screw is held at fractional tooth distances. 65

The bi-laterally symmetrical oblong base is equipped with truck wheels, normally clear of the ground, on the lower part of 70 the annex portion, whereby the jack can be readily tilted and wheeled about and up to the point of use, and when released settles upon its base without danger of overturning. According to a further feature of the 75 invention, the same long bar handle serves interchangeably for operating the lifting means and as a handle for trundling the jack.

Another part of the invention, having to 80 do with the manufacture, alignment and rigidity of the jack, relates to a sectional construction of the base, including in this term the inclosed supporting frame as a whole. 85

Still another feature relates to means whereby the pinions of the lifting and lowering mechanisms may be readily and accurately centered with respect to their gears, which is a matter of substantial importance 90 in view of the heavy loads which the jack is required to lift.

Further objects and features will become apparent as the specification proceeds.

In the drawings forming a part hereof: 95

Figure 1 is a side elevation of the jack tilted for wheeling, truck fashion;

Fig. 2 is a rear elevation showing the bar handle socketed in the lifting rocker and representing in broken lines one of the lifting handles in its horizontal or operative position; 100

Fig. 3 is a vertical section taken in the central axial plane of the standard and annex portions;

Fig. 4 is a vertical section through the

annex at right angles to Fig. 3, the plane of the section being indicated therein at 4—4;

Fig. 5 is a horizontal section on the line 5—5 of Fig. 3;

Fig. 6 is a horizontal section through the annex on the line 6—6 of Fig. 4;

Fig. 7 is a horizontal section on the line 7—7 of Fig. 4, looking up;

Fig. 8 is a horizontal section on the line 8—8 of Fig. 3;

Fig. 9 is a view partly in elevation and partly in vertical section showing the parts in the upper portion of the annex;

Fig. 10 is a perspective detail view of an element seen in Fig. 9;

Fig. 11 is an elevation of the common vertical operating shaft; and

Fig. 12 is a detail vertical section of a warning signal.

The inclosed base frame as a whole is designated 1. It comprises a relatively broad bottom or base portion proper 2 of oblong dimensions, a hollow, preferably cylindrical, standard portion 3, and an annex or extension portion 4 lower than the standard portion and located at the region which may be termed the back of the jack. Transverse axles 5 pass through tubular housing extensions 6 in the bottom of the annex portion, somewhat above the plane of the supporting base and at the rear of the longer dimension thereof. On the ends of this axle are small truck wheels 7, which normally clear the ground by a short distance. The annex partly overhangs the rear of the base.

The base is closed in order that the mechanism may operate in a body of grease, thereby materially increasing the efficiency of the jack. As preferably constructed it is made in three sections, comprising a low oblong bottom section 8, a relatively narrow standard section 9 having a widened lower portion 10 to conform with the bottom section whereon it rests, and an annex section or hood 11, which is applied against the backs of the other two sections. The interiors of the sections, where they meet, are open to each other, so as to form one general interior. The bottom section has an upwardly projecting, partly circular, inner flange 12 forming a rabbet, which is machined to receive the machined, partially circular lower rim 13 of the standard section, whereby these two sections are alined. The inner edge faces of the annex section lie in a vertical plane against corresponding machined surfaces of the standard and bottom sections, as indicated at 14 in Fig. 5, so that by aid of bolts 15 the whole is locked rigidly together, the sections being further interlocked by side flanges 16 on the lower part of the standard section embracing the annex section, as seen in Fig. 1, and by a lug 17 on the upper part of the standard section fitting a recess

in the top of the annex, as indicated in Fig. 3. At the bottom, a finished surface on the annex section rests at 18 upon a supporting surface on the section 8.

The said bottom section has a circular upward projecting rib 19 formed therein, in concentric relation to the alining flange 12, for the purpose of affording a centering seat for a broad end-thrust ball-bearing which rotatably supports an upstanding screw 20. Said bearing comprises a bottom circular ball-plate 21 having a central opening containing a side-thrust bearing bushing 22, an upper ball-plate 23 tight on a reduced unthreaded lower portion 24 of the screw, and an interposed series of balls 25. A large gear 26 is fixed rigidly on the lower part of the screw, against a shoulder 27, and applies the load to the upper ball-plate. The lower end of the screw shaft projecting below said upper ball-plate forms a journal 28, which revolves in the bearing 22.

A long circular slide-bearing 29 is machined at the top upon the interior of the standard 9 concentric with its bottom alining rim 13; and in this bearing works a cylindrical ram 30. A longitudinal groove 31 formed in the exterior of the ram receives a vertical spline 32 held by screws 33 in the upper part of the standard and keeps the ram from turning as it moves up and down. A relatively small diameter head 34, of approximately the width of the standard 9, is fixed to the upper end of the ram, of which it forms a part, the head having a downwardly projecting, interior, circular flange 35, which enters the ram and is there secured by screws 36. A packing gasket 37 in a groove in the bearing portion of the standard just below the top opposes the escape of grease when the ram ascends and keeps out dirt and grit when the ram descends and a screw plug 38 in the head permits of the introduction of the lubricant.

In the lower end of the ram, against a shoulder 39, is fixed a nut 40, through which the screw 20 passes into the interior of the ram, where all its portion above the nut stands free. Both the screw and the nut have a pitch beyond the angle of repose, so that with load upon the head the ram will slide down if permitted, the nut rotating the screw.

The annex section of the base is cast with interior webs or brackets 41, 42, 43, near the top and bottom and at an intermediate point, respectively, which are bored for bearings. Openings are provided in the top and bottom of the annex, in line with the bearings, for the purpose of boring, and to permit assembling and disassembling, and are closed by screw plugs 44 and 45. In the said bearings is journaled a vertical operating shaft 46 common to the mechanism about to be described.

On a fluted portion 47 of the shaft immediately above its lower journal portion 48 is fixed a spur pinion 49, which meshes with the gear 26 on the lower part of the screw. An upwardly facing bevel gear 50 is fixed on the same fluted portion of the shaft, immediately above the pinion 49.

This gear will be termed for convenience the lifter gear. With it meshes a bevel pinion 51 carried by the inner portion of a transverse lifting shaft 52, which passes through one side of the annex. On its outwardly projecting portion is an oscillatory pawl rocker 53, which embraces a ratchet wheel 54 on a hexagon section 55 of the shaft. The rocker has a socket 56, which receives the tapered butt end of a long bar handle 57.

Above the intermediate bracket 43 the vertical shaft 46 bears a ratchet-wheel 58, fastened thereon by a key 59, said ratchet wheel constituting the driven member of an overrunning clutch. The driving member of said clutch is carried by a part 60 free on the cylindrical portion 61 of the shaft next above the ratchet. The lower portion of said free part has a depending circular flange 62 encircling the ratchet and formed with recesses 63 wherein a plurality of pawls 64, in this instance three, are pivoted on vertical pins 65. Springs 66 fastened to pins 67 in the recesses and strained over other pins 68 bear against the backs of the pawls and press the same into engagement with the teeth of the ratchet.

The relation between the pawls and the ratchet is such, it is to be observed, that the pawls engage the holding faces of the ratchet teeth in succession. This is most conveniently accomplished by equally spacing the pawls, and making the teeth on the ratchet of a number not a multiple of the number of pawls. The result is that, in lifting, the ram cannot sink back a distance proportional to more than a fraction of a ratchet tooth.

The upper portion of the part 60 is formed with the teeth of a self-locking gear 69, which is meshed by a self-locking worm pinion 70 on a transverse lowering shaft 71. By self-locking is, of course, meant that the gearing is irreversible, so that pressure applied by load on the ram and eventually transmitted to the worm pinion 70 is there solidly sustained, and consequently the lowering shaft must be turned in order that the ram may be allowed to descend. In this way lowering is effected rapidly and with little manual effort, since all that is required is to let off on the holding means, the ram being driven down by the load.

The lowering shaft 71 is located above the lifting shaft 52 and in a vertical plane perpendicular thereto. Its inner end is journaled in a bearing aperture 72 in the por-

tion of the annex section 11 which abuts the standard section 9, and its outer portion is journaled in a bearing 73 in a gland 74, which is screwed into an opening in the rear wall of the annex. The outer end 75 of the lowering shaft, within said gland, is squared, and the gland is recessed to permit the insertion of the socketed stem 76 of a removable rotary crank handle 77.

The gland 74 has a cylindrical portion 78 inwardly or forwardly of its screw-threaded portion 79, and said cylindrical portion fits closely an accurately formed cylindrical portion of the opening in the annex wall. Similarly, the lifting shaft 52 is journaled in a gland 81 having screw-threaded and smooth portions 82 and 83, the latter fitting an accurately formed opening in the frame. In this way the driving pinions are exactly centered with respect to their gears, which particularly in the case of the lifting mechanism is important.

Through the overrunning clutch the self-locking lowering means is connected with the vertical operating shaft assemblage, and thereby with the screw, in one sense only. This enables the lowering means, by rotation of its handle in one direction, positively to operate the train of mechanism to raise the ram, as is useful in running it up quickly to the load. When the handle is turned in the opposite direction it also enables the lowering means to let off on the steep-pitch screw so that the latter runs down under load, as heretofore explained; and when the lowering means is left stationary, the lifting means operated by the long pump handle 57 can operate the mechanism below the clutch and force the ram upward independently of the lowering means, which because of its self-locking character blocks the effort of the ram to descend as soon as manual lifting force is no longer applied to the handle.

When the ram is elevated and load is absent, it will not run down of its own accord, however, if the crank-handle 77 is turned in the direction for lowering, because its weight is not sufficient to overcome friction. Means are hereby provided whereby the lowering means may be coupled to the train of mechanism, for positive lowering of the ram, so that the lowering means will then drive the common vertical shaft or member 46 and therefore the screw in the direction in which the overrunning clutch would ordinarily act idly. Such coupling device may be embodied in various forms, but preferably it comprises a clutch collar 84 movable vertically on a portion of the shaft, above the free part 60, having ribs 85 which are engaged by slots in the collar. Said collar has a downwardly-projecting rim 86 formed on its edge with ratchet-teeth 87 facing in the desired direction, and coöperative with a complementary ring of teeth 88 on 130

the top of the part 60. A spring 89, interposed between the clutch collar and the part 60, normally holds the collar raised sufficiently to keep the teeth out of engagement.

5 The clutch member is actuated against the pressure of the spring by means of a yoke 90, which straddles the upper end of the shaft 46. The limbs of this element are slidable in grooves 91 in the top journal portion 92 of the shaft within the top bearing 41, and at their lower ends are out-turned feet 94 which bear against the top of the clutch collar 84. The yoke is depressible by a button 95 on the top of the annex chamber, having a stem 96 passing through an aperture in the top plug 44 and riveted below to a plate 97 resting on the upper end of the yoke.

10 The same ribs 85, which permit the clutch member 84 to move vertically on the shaft while holding it thereto against relative rotation, are utilized for retaining a locking ring 98, the function of which is to hold the part 60 in place upon the middle bracket 43. The said ring, as seen in Fig. 7, is formed 15 with slots 99 arranged to pass over the ribs, whereby the collar can be slipped downward until it lies in a groove or narrow unribbed zone 100 of the shaft just above the part 60, where a partial turn brings its solid portions beneath the lower ends of the ribs, so that the latter then block the collar against rising. In this position the collar is held against 20 turning by one or more set-screws 101.

25 The long handle 57 which is used in the socket 56 for lifting, by rotation of the screw effected by manual pump action, is also made available as the handle for tilting the jack and rolling it about on its truck wheels 7. For this purpose its lower end is placed, instead of in the rocker socket, in a fixed socket 102 on the lower back part of the annex, and its intermediate part is slipped between a pair of lugs 103, and there held by a transverse pin 104 passed through registering 30 holes provided in the lugs and bar. With this condition, with the handle secured substantially upright on the back of the jack, it is a simple matter to reach up and grasp the upper part of the handle and tilt the 35 jack off its flat bottom onto the wheels, and then to move it about as desired. In this operation, the center of gravity being low, there is no danger of overturning in event of one of the wheels riding over an obstacle; and when the jack is tilted forward and the 40 handle released, it settles promptly upon its bottom without tendency to rock over, being restrained by the weight disposed at the back in the annex.

45 Carrying handles 105 are pivoted at 106 to opposite sides of the base at about the level of the top of the annex and substantially in the vertical plane with the center of gravity. These handles are angled adjacent 50 their pivot points, so that upon raising them

the shoulders thus provided abut against the sides of the base and rigidly sustain the handles in the horizontal, carrying position.

55 A warning signal is provided to indicate when the ram has been lifted approximately 70 to the limit of safety. A dog 107 is pivoted at 108 between lugs 109 on the standard, at the region of the bearing 29. The wall of the standard is slotted to permit the nose on the lower end of the dog to bear through 75 the slot upon the side of the ram, under the action of a spring 110. The ram has a recess 111 near the lower end, terminating in an abrupt shoulder 112, the recess and shoulder being in vertical line with the warning signal. When the ram has been raised to the 80 permissible limit, the nose of the dog drops into the recess, and when it encounters the shoulder the resistance to further movement indicates to the operator that he has gone far enough. If he continues to force the jack, the dog acting as a rigid thrust member 85 shears off the pivot pin 108, so that the dog drops and by the noise of its fall upon the base gives further warning. 90

95 The operation of the jack will now be briefly set forth. The jack is moved about by inserting the long lever lifting handle 57 in the trundling sockets 102, 103 on the back of the annex and fastening it with the pin 104, whereupon the jack is tilted backward upon its truck wheels and pushed along to the place where needed. Because of the organization of the jack, with the operating mechanism in the base and consequently low 100 center of gravity, maneuvering is performed with safety and convenience, either of the wheels passing over a rise without the lateral inclination carrying the center of mass outside the base support. When the 105 jack is tilted forward onto its bottom again, the disposition of the mass and the relatively large area of the base, with its greater horizontal dimension parallel with the plane of tilting, and the weight of the annex and its 110 contents at the back, prevent all possibility of forward overturning, as heretofore explained.

115 The horizontal projection of the base beyond the lines of the standard and head is such as to permit the head to be positioned beneath the jacking point when the horizontal distance between the projection of the jacking point and an obstruction at the bottom is the minimum likely to be encountered 120 in railroad work, for which the jack is more particularly designed.

125 In jacking, the comparatively small diameter of the head in relation to the screw and bearings protects the screw, and avoids frictional resistance and strain from side thrust due to cantile load. The head is but slightly wider than the internal top bearing 29, and the incidence of the load is practically confined to the radius between 130

- the circuit of this bearing and the axis of the screw. The nut 40 applies the load to the screw at the lower end of the ram and constitutes an efficient center bearing with 5 out tending to bend the screw. At the bottom the screw is firmly planted upon a wide base afforded by the large gear 26 and the ball thrust bearing beneath it, and the lower extremity is stayed by the bearing 22. Both 10 in ascending and descending the head, ram and nut are held against rotation by the spline 32, the screw rotating upon its support in the fixed base, and the nut traveling up or down as the case may be.
- 15 In order to lift with the jack, the long bar 57 is removed from its fixed position in the trundling sockets and its extremity is placed in the pawl-rocker socket 56. Then the operator, standing behind the annex, 20 works the handle up and down, rotating the lifting shaft 52 and its pinion 51 in a step-by-step manner, thereby turning the lifter gear 50, the common vertical operating shaft 46, the spur pinion 49, the screw gear 25 26, and the screw 20, thus causing the nut 40 and the ram and head to rise. In this operation the ratchet member 58 of the overrunning clutch revolves with the rest of the assemblage fast on the common shaft 46, 30 the teeth of the ratchet clicking idly past the pawls 64 of the other member of the clutch connected with the lowering means, which remains stationary. On each up-stroke of the sweep handle, during which 35 power is not applied to the lifting mechanism, the effort of the loaded ram to run down the steep-pitch screw is held by the worm pinion 70 of the self-locking lowering means, the overrunning clutch then acting 40 as a rigid connection, as will be apparent. By virtue of the vernier action of the clutch heretofore explained, the sink-back or settling of the ram before the clutch takes hold is reduced or practically eliminated. In the lifting of heavy loads this is 45 an important factor in prolonging the life of the apparatus, as the shock in such cases from a drop commensurate to the length of a ratchet tooth is severe; and in addition, 50 of course, labor is saved, because the negative work required of the operator is minimized.
- The ram and head can be quickly raised to the jacking point, by inserting the rotary 55 crank-handle 77 in its socket in the gland 74 and revolving the worm pinion 70 of the lowering means in the proper direction, thereby turning the worm gear 69 and with it the member 62 of the overrunning clutch.
- 60 In this case, the clutch acts as a rigid connection, and the ratchet 58, shaft 46 and the rest of the train leading to the screw 20 are driven so as to elevate the ram. When the head reaches the part to which lifting 65 power is to be applied, the pump handle 57
- is operated to actuate the lifting mechanism in the manner just described. The relations are such, it will be observed, that the handles of both the lifting and the lowering mechanisms are presented for operation behind 70 the annex portion of the base.
- The load is held, as stated, at any point by the self-locking lowering means. In order to lower, the crank-handle 77 is turned in the direction reverse to that for quick 75 raising, thus allowing the worm-gear 69, and through it the overrunning clutch 62, 58, the shaft 46, the pinion 49, the screw gear 26 and the screw, to revolve, and thereby, in turn, permitting the nut 40, with the ram 80 and head, to run down.
- If the ram is elevated and no load is resting thereon, it will not, as previously stated, slide down by itself on merely letting off on the holding means. Under such condition, the operator pushes down on the button 95 on the top of the annex, thereby 85 through the yoke 90 depressing the spring-sustained clutch member 84 to cause its teeth 87 to engage with the clutch teeth 88 90 on the part 60. These teeth are so fashioned as to form a positive connection between the lowering means and the shaft 46 in respect to effort transmitted from said means to the shaft in the lowering direction. Consequently, by then turning the rotary crank-handle as if for lowering in the regular way, the operator drives through the self-locking lowering means and the common vertical shaft to the screw and compels the nut and 100 ram to descend.
- This completes the description of the preferred embodiment of the invention, other forms and modifications of which may be devised by the mechanic.
- What we claim as new is:
1. In a high-speed jack, the combination of a base, a ram, a rotary steep-pitch screw member in the base coacting with the ram, a common vertical operating shaft in the 110 base geared at the bottom to said screw member, and two operating mechanisms in the base operative through said common vertical shaft, one being a lifting mechanism geared to the shaft and the other a holding 115 and lowering mechanism having an overrunning connection therewith.
  2. A high-speed jack, comprising, in combination, a base with a hollow standard and an annex, a hollow ram slidably guided in 120 the standard and bearing a nut in its lower portion, a steep-pitch screw rotatably supported in the base and extending upward through the nut into the interior of the ram, a common vertical shaft in bearings in the 125 annex of the base geared at the bottom to the screw, a lifting means, and a self-locking lowering means, both on said shaft.
  3. A high-speed jack, comprising a base, a ram having a nut, a steep-pitch screw ro- 130

- tatably supported in the base and extending through said nut and freely within the ram, a common operating shaft in the base parallel with the vertical screw and ram and 5 geared to the lower part of the screw, a lifting means connected with a lower part of said common shaft, and a holding, lowering and raising means having an overrunning connection with an upper part of the shaft.
- 10 4. A high-speed jack, comprising a base, a ram having a nut, a steep-pitch screw rotatably supported in the base and extending through said nut and freely within the ram, a common operating shaft in the base parallel with the vertical screw and ram and 15 geared to the lower part of the screw, upper and lower transverse shafts in the base, the lower transverse shaft being geared to the common operating shaft and having an 20 actuating rocker for lifting, the upper transverse shaft having rotary handle operating means, a self-locking gearing operable by the upper shaft and having its driven part coaxial with the common operating shaft, 25 and an overrunning connection between said driven part and the common shaft.
5. A high-speed jack having an inclosure comprising a base with hollow standard and an annex chamber, a ram slideable in the 30 standard, a nut in the lower part of the ram, a steep-pitch screw rotatably supported at its lower end in the base and extending upward through the nut and freely within the ram, bearings in the annex chamber of the 35 base, a vertical main operating shaft journaled in said bearings, meshing gears on the lower portions of the shaft and screw, a bevel gear on the lower part of said shaft, a transverse lifting shaft journaled in the 40 annex chamber and having an oscillatory operating device and a bevel pinion meshing the said gear, a transverse shaft in the upper part of the annex chamber having a rotary operating device, meshing gear elements 45 operated by the last-named shaft, the driven member of said elements being free on the vertical shaft, and an overrunning connection between said member and the vertical shaft.
- 50 6. In a high-speed jack, the combination of a base, a ram with nut, a steep-pitch screw in the base extending upward through the nut within the ram, a vertical main operating shaft in the base geared at the bottom 55 to the screw, lifting means geared to a lower part of said shaft, a ratchet wheel fixed on the shaft above the lifting means, a pawl-carrier loose on the shaft above the ratchet, a gear element united with the pawl-carrier, 60 and a transverse crank handle shaft having a pinion element meshing with said gear element.
- 65 7. A high-speed jack comprising a base, a ram, a steep-pitch screw rotatable on the base for operating the ram, two sets of

meshing gears in the base with handles for operating the same, the two sets of gears having members on a common vertical shaft and an overrunning clutch associated with one of them, and common meshing gears on 70 the lower parts of the screw and shaft through which both of the operating gearings coöperate with the screw.

8. In a high-speed jack, the combination of a base, a ram, a steep-pitch screw rotatable 75 on the base for operating the ram, a shaft in the base parallel with the screw and ram, a lifting mechanism, and a holding and lowering mechanism with overrunning connection, both operating on said shaft, and 80 meshing gears at the base of the shaft and screw.

9. In a high-speed jack, the combination of a base, a ram, a rotary steep-pitch screw member in the base coacting with the ram, 85 a gear on the lower part of the screw member, rotary parts united on a common vertical axis at one side of the screw member comprising a pinion meshing with said gear, a lifter gear and a member of an overrunning clutch, another gear and the other member of the overrunning clutch united with each other and coaxial with said parts, a lifting device having a pinion meshing with the lifter gear, and a second operating 90 device having a pinion meshing with said other gear.

10. In a high-speed jack, the combination of a base, a ram, a rotary steep-pitch screw member in the base coacting with the ram, 100 a gear on the lower part of the screw member, rotary parts united on a common vertical axis at one side of the screw member comprising a pinion meshing with said gear, a lifter gear above said pinion and a member of an overrunning clutch above the lifter gear, another gear and the other member of the overrunning clutch united with each other above and coaxial with said parts, and operating devices coöperative respectively 105 with said lifter gear and said other gear.

11. In a high-speed jack, the combination of a base and standard, a ram slideable therein, a steep-pitch screw for operating the ram, a lifting mechanism geared to the 115 screw, a lowering mechanism for the screw, a rotary part through which said lowering mechanism normally coöperates with the screw, an overrunning clutch between said lowering mechanism and said part, and 120 a device for coupling the lowering mechanism to said part for positive lowering.

12. In a high-speed jack, the combination of a base, a ram, a steep-pitch screw member rotatably supported in the base for actuating the ram, an assemblage on a common vertical axis in the base geared to said screw member, a lifting mechanism geared to said assemblage, a free member coaxial with said assemblage, a holding and lowering means 125 130

connected with the free member, an overrunning clutch between the free member and the assemblage, and another clutch movable to couple the free member to the assemblage for positive reverse operation.

13. In a high-speed jack, the combination of a base, a ram, a steep-pitch screw member rotatably supported in the base for actuating the ram, a vertical common rotary shaft in the base geared at the bottom to the screw member, a lifter gear and a member of an overrunning clutch fast on said shaft, lifting means coacting with the lifter gear, a part free on said shaft including a gear and the other member of the overrunning clutch, a lowering device having a pinion meshing with the last mentioned gear, and a vertically movable spring-released clutch for coupling the free member to the common shaft for positive lowering.

14. In a high-speed jack, the combination of a base, a ram, a steep-pitch screw member rotatably supported in the base for actuating the ram, a vertical rotary shaft in the base geared at the bottom to the screw member, a lifter gear and a member of an overrunning clutch fast on said shaft, lifting means coacting with the lifter gear, a part free on the shaft above said elements having a gear on its upper portion and the other member of the overrunning clutch on its lower portion, a lowering device having a pinion meshing with the last-mentioned gear, and a vertically movable clutch at the top of the free part for coupling the same to the shaft for positive lowering.

15. A high-speed jack, comprising a base having a hollow standard and an annex, a hollow ram slidable in the standard and bearing a nut, a steep-pitch screw rotatably supported at the bottom in the base and extending upward through the nut into the interior of the ram, a vertical shaft in the annex geared at the bottom to the screw, lifting means in the annex geared to said shaft, holding and lowering means in the annex having a part free on the upper portion of said shaft, an overrunning clutch between said free part and the shaft, a clutch for coupling the free member with the shaft for positive lowering, and a member in the top of the annex for operating this clutch.

16. A high-speed jack, comprising a base having a hollow standard and an annex, a hollow ram slidable in the standard and bearing a nut, a steep-pitch screw rotatably supported at the bottom in the base and extending upward through the nut into the interior of the ram, a vertical shaft in the annex geared at the bottom to the screw, lifting means in the annex geared to said shaft, holding and lowering means in the annex having a part free on the upper portion of said shaft, an overrunning clutch

between said free part and the shaft, a spring-raised clutch member slidably engaged with the shaft above the free part, a yoke slidable in grooves in the upper end of the shaft, and an actuator for depressing the yoke.

17. A high-speed jack, having a base, a ram bearing a nut, a steep-pitch screw in the base, a vertical shaft in the base geared to said screw, raising means in the base 75 geared to said shaft, holding and lowering means having a part free on the upper portion of the shaft, an overrunning connection between said part and the shaft, the portion of the shaft above said part being ribbed 80 with a groove at the base of the ribs, a locking ring slotted to pass the ribs and held in said groove, and a clutch member slidably engaged with said ribbed portion of the shaft for coupling the free part to the shaft. 85

18. A high-speed jack comprising, in combination, a base having a hollow standard rising therefrom and containing a rigid bearing in its interior, a hollow ram slidable in the bearing of the standard and having 90 a small head at its upper end and a nut in its lower portion, a steep-pitch screw supported rotatably in the base and extending upward through the nut, a lifting mechanism and a holding and lowering mechanism, both mounted in the base and having connection with the lower part of the screw. 95

19. A high-speed jack comprising, in combination, a base having a hollow standard rising therefrom and containing a rigid bearing in its interior, a hollow ram slidable in the bearing of the standard and having a small head at its upper end and a nut in its lower portion, means to keep the ram from turning in the standard, a steep-pitch screw supported rotatably in the base and extending upward through the nut, a lifting mechanism and a holding and lowering mechanism, both mounted in the base and having connection with the lower part 110 of the screw. 105

20. A high-speed jack comprising a base and standard, and a hood applied thereto forming an annex chamber, a steep-pitch screw and ram in the base and standard, and lifting and lowering mechanisms assembled on a common vertical shaft in said annex chamber with an overrunning connection for the lowering mechanism, and meshing gears at the base of the shaft and screw for both 115 mechanisms. 120

21. A high-speed jack, comprising, in combination, a base with a hollow standard and an annex, a hollow ram slidably guided in the standard, steep-pitch screw and nut 125 mechanism within the base and ram, and operating mechanism comprising a lifting means and a lowering means on a common vertical axis in the annex of the base.

22. A high-speed jack, comprising a base, 130

a ram having a nut, a steep-pitch screw in the base coacting with the nut, a vertical shaft in the base geared to the screw, a gear on the shaft, the base having a transverse smooth centering opening, a gland having a 5 smooth cylindrical centering portion fitting said opening and means for fastening the gland in place, and an operating shaft journaled in the gland and bearing a pinion 10 meshing with said gear.

23. In a high-speed jack, the combination with the vertically movable part, steep-pitch screw means for actuating the same, a lifting means geared to the screw means, and a holding and lowering means, of an overrunning connection between the holding and lowering means and the screw means comprising a ratchet and a pawl-carrier containing a plurality of pawls successively 15 operative with the ratchet teeth.

24. A high-speed jack, comprising a base having a hollow standard and an annex, a hollow ram slideable in the standard and having a nut at the bottom, a steep-pitch screw 20 rotatably supported in the base to coöperate with said nut, a gear on the lower portion of the screw, a vertical shaft in the annex, upper and lower bearings and an intermediate bearing in the annex for said 25 shaft, a pinion meshing with the gear on the screw and a lifter gear fast on the shaft above the lower bearing, a ratchet fast on the shaft above the intermediate bearing, a part free on the shaft above the ratchet and 30 including a gear and a pawl-carrier, lifting means coöoperative with the lifter gear, and holding and lowering means coöoperative 35 with the upper gear.

25. A high-speed jack having a casing 40 comprising a bottom section, a standard section and an annex section applied to the back of the bottom and standard sections, a ram slideably guided in the standard section and having a nut, a steep-pitch-screw rotatably supported in the bottom section, a common 45 vertical shaft in the annex section, meshing gears on the lower portions of said shaft and screw, a lifting mechanism, and a holding and lowering mechanism, both on 50 said vertical shaft.

26. A high-speed jack, having a casing

comprising a bottom section, a standard section, and an annex section, a ram slideably guided in the standard section and having a nut, a steep-pitch screw rotatably supported in the bottom section, and operating mechanism in the annex section, the bottom and standard sections having coaxial alining means, and the annex section interlocking with both.

27. A high-speed jack, having a casing comprising a bottom section containing a ball-bearing seat, a standard section having an internal slide bearing, concentric alining formations on the meeting portions of said sections, a ram slideable in said bearing and having a nut, a screw extending upward through the nut freely into the interior of the ram, a ball-bearing in said seat rotatably supporting the screw, an annex section applied to both said sections and locking them against relative rotation, and operating mechanism in the annex section.

28. A jack, comprising a base having a hollow standard and a rear annex, a ram slideably guided in the standard, a screw for lifting the ram, and operating mechanism in the annex, in combination with a pair of truck wheels normally off the ground at the lower portion of the annex, and 75 handle means on the annex for tilting the jack onto its wheels and trundling it about.

29. In a jack, a base, a ram, a screw for actuating the ram, and lifting mechanism having an oscillatory handle socket, in combination with truck wheels on the base normally off the ground, a trundling socket on the base whereby the jack can be tilted off its base onto the truck wheels; and a long 80 handle engageable interchangeably with said 85 sockets.

30. A jack having a base with a standard and rear annex, a screw-operated ram in the standard portion of the base, operating mechanism in the annex portion thereof, and 90 truck wheels at the lower annex region normally clear of the ground, to support the jack for trundling when tilted rearward off its base.
